UNITED STATES PATENT OFFICE.

CHARLES O. ELLINWOOD, OF RYE BEACH, NEW HAMPSHIRE.

DESIGN FOR A WORK-HOLDER.

SPECIFICATION forming part of Design No. 30,559, dated April 18, 1899.

Application filed March 14, 1898. Serial No. 708,096. Term of patent 14 years.

To all whom it may concern:

Be it known that I, CHARLES O. ELLINWOOD, a citizen of the United States, residing at Rye Beach, in the county of Rockingham and State 5 of New Hampshire, have invented and produced a certain new and original Design for a Work-Holder; and I do declare the following to be a full, clear, and exact description of the invention, such as will enable others skilled in the art to which it appertains to make and use the same.

The invention relates to a new and original design for a work-holder; and it consists of a design of the configuration and ornamentation shown in the accompanying drawings, in 15 which—

Figure 1 is a perspective view, and Fig. 2 is a top plan view, of my invention.

The leading features of the design consist 20 in the side plates *a* and *b*, the edges of which are curved and terminate in the apices *c* and are connected by the base-piece *d*.

e denotes rods projecting from the side

plates, and *f* denotes a bail projecting from the apex of one plate to that of the other 25 plate.

g denotes a bulged piece projecting from one of the plates, and *h* denotes a bulged piece projecting from the other plate. These bulged pieces, as well as each of the plates, have 30 holes *i* extending through them in the shape or ornamentation of a three-leaf clover.

j denotes pins projecting vertically from the base-piece.

Having thus described the invention, what 35 is claimed and desired to be secured is—

The design for a work-holder, as herein shown and described.

In testimony whereof I have hereunto set my hand in presence of two subscribing witnesses. 40

CHARLES O. ELLINWOOD.

Witnesses:

JOHN H. BARTLETT,
CALVIN PAGE.
